ATTORNEY.

UNITED STATES PATENT OFFICE.

FREDERICK GIRTANNER AND ALICE GIRTANNER, OF NEW YORK, N. Y.,
ASSIGNORS TO UNITED STATES MINING & TRADING CO., A CORPORATION OF NEW YORK.

SMOKELESS SELF-CLEANING GRATE.

SPECIFICATION forming part of Letters Patent No. 757,187, dated April 12, 1904.

Application filed July 11, 1903. Serial No. 165,038. (No model.)

To all whom it may concern:

Be it known that we, FREDERICK GIRTANNER and ALICE GIRTANNER, citizens of the United States of America, residing at the city of New York, in the county of New York and State of New York, have invented certain new and useful Improvements in Smokeless Self-Cleaning Grates, of which the following is a specification.

10 Our invention has reference to smokeless self-cleaning grates for steam-boiler furnaces or other furnaces, and particularly to that class known as "traveling" grates, to which the fuel is fed from a hopper, the whole being commonly known as "mechanical stokers."

The primary object of our invention is to provide a furnace-grate in which the fuel is continually carried on traveling surfaces and the grate rendered self-cleaning by an intermediate roll or rolls and a coöperating end roll, thus always preserving a clean fire without hand raking or dressing, while at the same time complete combustion without smoke is accomplished.

25 With this object in view our invention consists, essentially, in a self-cleaning furnace-grate comprising a plurality of traveling grates arranged contiguous to each other and an intermediate clearing-roll, and also in a self-cleaning furnace-grate comprising a plurality of traveling grates arranged contiguous to each other, an intermediate clearing-roll, and an end clearing-roll.

The nature of our invention will best be understood when described in connection with the accompanying drawings, in which—

Figure 1 represents a side elevation of a grate embodying our invention, the same being shown applied to a boiler-furnace, which latter is shown in section. Fig. 2 shows a modification of part of the grate.

Similar letters and numerals of reference designate corresponding parts throughout both views of the drawings.

45 Referring now to the drawings, the letter A designates a hopper into which the fuel charge is supplied either by hand or by a chute in a

usual manner, the same being provided with a discharge-opening for delivering the fuel to the first traveling grate B. Contiguous with 50 said grate B is arranged a second traveling grate C, preferably inclined and adapted to receive the fuel discharged from the first traveling grate, and between the two adjacent ends of the two grates, which are at different levels, 55 is placed a clearing-roll D. The traveling grate B is moved forwardly by means of a suitable worm-wheel 1, engaging with a rack 3, attached to or forming part of the grate, and said worm-wheel being mounted on a shaft 60 driven by any suitable means—for instance, a small motor M, driving a worm-shaft 4, engaging with said worm-wheel. The second or inclined grate is driven by a chain-wheel 5, mounted on the shaft 6 of the end wheel 7 of 65 the said grate, the other end of the second grate running over a chain-wheel 9, mounted on a shaft 10, both said grates traveling in practically the same direction. At the terminal of the second grate C is mounted a second clearing-roll E, placed substantially on a level with the end shaft 10 of the grate and adapted to divert the flow of ashes downwardly in view of the rotary movement of the bars of the grate opposite to such clearing- 70 roll, thus completely removing all remaining ashes at this point.

The function of the clearing-roll D is to intersect and break up any and all clinkers which may be formed on the first traveling 80 grate B, delivering or discharging the same into the ash-pit below continuously during the movement of the traveling grates. Such portions of the clinkers as may pass over to the second grate are discharged through the 85 agency of the rear clearing-roll E and if of sufficient size are crushed or broken up by said roll.

It is of course to be understood that the traveling grates may be of any well-known 90 construction permitting the ashes to discharge between the bars and that the clearing-roll D is so spaced as to permit the passage of ashes between it and the traveling grates.

In practice we prefer to corrugate or flute the clearing-rolls, although they may be made practically plain.

It is of course to be understood that in place of two traveling grates three or more may be arranged in line, preferably with intermediate clearing-rolls either between all the adjoining grates or alternating between grates, the last grate being preferably inclined, as shown in the drawings, or in case of long furnaces one or more of the rear traveling grates may be inclined.

It is of course to be understood that both clearing-rolls, D and E are mounted to turn freely with or upon their shafts, although they could be driven slowly in the proper discharging directions.

In the modification shown in Fig. 2 we have omitted the intermediate clearing-rolls D, the ends of the grates being arranged as closely as possible together for permitting passage without interference.

What we claim as new is—

1. A self-cleaning furnace-grate comprising a number of traveling grates arranged

contiguous to each other and an intermediate clearing-roll, substantially as described.

2. A self-cleaning grate comprising a plurality of traveling grates arranged with their adjacent ends at different levels, and a clearing-roll arranged at the end of the last traveling grate and having its periphery projecting above and below the axis of the end shaft of the said grate, substantially as described.

3. A self-cleaning furnace-grate comprising a number of traveling grates arranged contiguous to each other, an intermediate clearing-roll adapted to crush and clear the clinkers intermediate of the adjacent ends of the grate, and an end clearing-roll, substantially as described.

In testimony whereof we have hereunto set our hands in the presence of two subscribing witnesses.

FREDERICK GIRTANNER.
ALICE GIRTANNER.
